UNITED STATES PATENT OFFICE.

GEORGE W. PLUMMER, OF NEWARK, NEW JERSEY.

DESIGN FOR BLACKBOARD-ERASER HANDLES.

Specification forming part of Design No. 7,447, dated May 19, 1874; application filed April 20, 1874.
[Term of Patent 7 years.]

To all whom it may concern:

Be it known that I, GEORGE W. PLUMMER, of Newark, in the county of Essex and State of New Jersey, have invented a Design for Handle or Stock for Blackboard-Erasers, of which the following is a specification:

This invention relates to a new and ornamental design for the stock or handle of a blackboard-eraser; and the design consists in forming the said stock with alternate plain and beveled surfaces running round the sides and ends of the block, as shown.

A narrow plain surface, *a*, is next the front face or rubbing-surface of the handle or stock, and a corresponding narrow plain surface, *b*, is next the body or back of the stock. From each of these plain surfaces there extend inward two beveled surfaces, *c d*, which join a plain surface or belt, *e*, the beveled surfaces being connected to each other at the plain belt *e*, then at the points of beginning.

It will be seen from the foregoing brief ex-

planation of the design, as represented by the drawing, that I provide the handle or stock of a blackboard-eraser with a finger-groove that, instead of being bounded by a curved line, as usual, is bounded by two narrow plain surfaces, two broad beveled surfaces, and one broad plain surface, thereby imparting to the device a neat and attractive appearance, and one by which it may be readily distinguished from like devices as well as brush-blocks now in the market.

What I claim as my invention, and desire to secure by Letters Patent, is—

The design for a handle or stock for blackboard-erasers, as herein shown and described.

In testimony whereof I have hereunto set my hand this 18th day of April, 1874.

GEO. W. PLUMMER.
